UNITED STATES PATENT OFFICE

109,949

DESIGN FOR A FOOD CABINET

Cyrus F. Hoffman, Trenton, N. J., assignor to C. V. Hill & Co., Inc., Trenton, N. J., a corporation of New Jersey

Application August 16, 1937, Serial No. 71,140

Term of patent 14 years

To all whom it may concern:

Be it known that I, Cyrus F. Hoffman, a citizen of the United States of America, residing at Trenton, in the county of Mercer and State of New Jersey, have invented a new, original, and ornamental Design for a Food Cabinet, of which the following is a specification, reference being had to the accompanying drawings, forming part thereof.

cabinet showing my new design.

Only one end of the cabinet is provided with a grill.

I claim:

The ornamental design for a food cabinet substantially as shown and described.

CYRUS F. HOFFMAN.
